UNITED STATES PATENT OFFICE.

DAVID H. ALLEN, OF MIAMISBURG, OHIO.

TOBACCO-PIPE-CHARGING DEVICE.

SPECIFICATION forming part of Letters Patent No. 679,872, dated August 6, 1901.

Application filed October 1, 1900. Serial No. 31,603. (No model.)

To all whom it may concern:

Be it known that I, DAVID H. ALLEN, a citizen of the United States, residing at Miamisburg, in the county of Montgomery and 5 State of Ohio, have invented certain new and useful Improvements in Tobacco-Pipe-Charging Devices, of which the following is a specification.

The object of my invention is to provide a 10 tobacco-pipe-charging device so constructed as to afford easy and convenient means for filling from a receptacle containing tobacco without the necessity of taking the tobacco into the hands.

15 The features of my invention are more fully set forth in the description of the accompanying drawings, forming a part of this specification, in which—

Figure 1 is a perspective bottom view of 20 the charger. Fig. 2 is a side elevation showing the same attached to a bag. Fig. 3 is a central cross-section of Fig. 1. Fig. 4 is a longitudinal vertical section of Fig. 1. Fig. 5 is a perspective view of the inner cylinder. 25 Fig. 6 is a longitudinal vertical section of a modification.

The charging device is composed of two barrels A B. The outer barrel A is provided with a hopper a, which surrounds a longitudinal opening b. The inner barrel B is provided with a corresponding opening c.

d represents an annular ring fitted upon the outside of the barrel at one end of said inner barrel, which affords convenient means 35 for manipulation.

e represents a flanged head partially closing the inner barrel at the opposite end. It is provided with a tubular projection or nozzle f, connecting with the interior of the cylinder and adapted to fit the bowl of a pipe.

The outer barrel A concentrically journals upon the inner barrel. The openings of the two barrels into the hopper are caused to coincide by turning the inner cylinder so that 45 the tobacco from any receptacle may be admitted into the inner barrel, from whence it is conveyed into the pipe. When it is desired to close the tobacco-charger, the inner barrel is revolved until its solid section closes

50 the opening b of the outer barrel. The ends of the combined barrels opposite the tubular

end f is open, so that the finger may be inserted to force the charge of the tobacco into the bowl of the pipe.

This charging device may be attached to 55 any receptacle. In Fig. 2, D represents a bag or sack secured to the hopper a with a drawstring g for closing the sack under the hopper. This is a very convenient means of carrying the tobacco and charger. Any other 60 receptacle may be employed in lieu of the bag or sack.

In Fig. 6 the outer barrel A is provided with the tubular projection or nozzle f and hopper a, and the inner barrel B, after it is 65 inserted within the outer barrel, is held securely in position by a lug h, sliding against a side of the hopper a.

It is obvious that various methods of constructing the inner and outer barrels may be 70 devised in accordance with the spirit of my invention, though differing from the precise form shown.

Having described my invention, I claim—

1. In a tobacco-charger, an outer barrel and 75 a movable barrel concentrically journaled within the outer barrel, feeding- orifices pierced through the sides of said barrels adapted to register with each other, a hopper attached to the outer barrel and surrounding 80 the filling-orifices, the lower end of the barrel being provided with a nozzle adapted to fit in the bowl of a pipe, and a finger-opening at the top of both of said barrels, substantially as specified. 85

2. A tobacco-charger composed of a bag, an outer barrel, a hopper attached thereto and to said bag, an inner barrel concentrically journaled within the outer barrel, orifices pierced through the sides of said barrels 90 adapted to register each with the other, a nozzle adapted to fit the bowl of a pipe fixed to the lower end of the barrel, and a finger-opening through both of said barrels, substantially as specified. 95

In testimony whereof I have hereunto set my hand.

DAVID H. ALLEN.
